ATTORNEY.

UNITED STATES PATENT OFFICE.

WILLIAM P. QUENTELL, OF NEW YORK, N. Y., ASSIGNOR TO QUENTELL CORPORATION,
A CORPORATION OF NEW YORK.

CALCULATING MACHINE.

Application filed August 16, 1921. Serial No. 492,659.

To all whom it may concern:

Be it known that I, WILLIAM P. QUENTELL, a citizen of the United States, residing at New York, in the county of New York 5 and State of New York, have invented or discovered certain new and useful Improvements in Calculating Machines, of which the following is a specification, reference being had therein to the accompanying drawings.

10 This invention relates to certain improvements on the calculating machine covered by my U. S. Patent No. 1,104,385, dated July 21, 1914. In the construction shown by my said patent each index member is locked to 15 an adding member and moves with it during the full travel of said adding member when multiplication is being performed. In practice, however, it has been found that this is objectionable, in that there was too much 20 weight of metal to be oscillated with the adding members during addition and also during multiplication. In accordance with the present invention the index members have but very short movements and each adding 25 member consists of two separate parts one comprising a sector gear or rack bar and the other comprising a stop-arm part which cooperates with the index member and which stop arm part and index member may remain stationary when multiplication is being done. The object of the present invention 30 is to simplify the construction and thereby reduce the cost of production, as well as to increase the speed at which the 35 machine may be operated.

In the accompanying drawings Fig. 1 is a sectional view of a calculating machine embodying the present invention, the section being taken on line 1—1, Fig. 2, looking 40 in the direction of the arrows adjacent said line. Fig. 2 is a partial broken out plan view of the same. Fig. 3 is a sectional elevation looking from the bottom of Fig. 4, and Fig. 4 is a plan view of the mechanism 45 illustrated in Fig. 3. Fig. 5 is a detail front view showing certain parts as they appear looking from the left of Fig. 1 in the direction indicated by the arrows 5.

Referring to the drawings, A denotes a 50 portion of the left side frame part of the machine which latter comprises a corresponding right side frame part. Extending transversely of the machine are two slotted bars or combs 12 and 13, near the front and 55 top of the side frame parts, these transverse

slotted bars being connected with the side frame parts and being preferably of channel shape in cross-section. Secured to the said transverse bars 12 and 13 are a series of strips 14 on which are placed the digits 60 1 to 9, inclusive. The figures or digits of each of these strips represent certain numbers or values which are to be added, and the several strips comprising the series represent certain values beginning with units, 65 at the bottom or right hand strip and running thence into tens, hundreds, thousands, etc. for the series.

Adjacent each of the strips 14, and movable in slots in the bars 12 and 13, are index 70 members 15, these index members being preferably provided on their outer sides with a series of projections affording finger recesses 15^a corresponding in number to the digits on the strips 14 and which digits, as 75 above stated, represent certain values to be added, the said index members being provided on their inner sides with a series of ratchet teeth 15^b. These index members are normally held in raised position by coil 80 springs 16 connected with the upper transverse bar or comb 13, and with the upper ends of said index members 15.

Extending transversely of the machine is an operating shaft 17 which, in practice, will 85 be provided at its right hand end with an operating handle as in the machine of my said patent. Loosely mounted on the shaft 17 are the adding member parts 18 and 19, which are constructed at their inner or bearing ends as yokes 18^a and 19^a, the former embracing the latter. One set of these adding member parts is provided for each of the index bars 15. Each adding member part 18 is in the form of a stop arm to the 90 outer end of which is pivoted a pawl 20 having a looped outer end 20^a embracing an index bar 15. Each pawl 20 is provided with a side lug 20^b which is intended for co-operation with the ratchet teeth 15^b on an 100 index bar or member 15, as will be explained. Each stop arm part 18 is also provided with a lateral projection 18^b arranged for engagement with the hooked portion of a latch 21 pivoted on a transverse bar 22, 105 the pivoted portion of said latch being formed as a loop or bail 21^a (see Fig. 5) arranged to be engaged by the depending lower end portion or tail 15^c of an index bar 15. Each pawl 20 is engaged by a frie- 110

- tion spring 23 to prevent a too free movement thereof, and which friction springs will retain said pawls in place until they are positively operated, as will be explained. 5 Connected with the lower end of each latch 21 is a coil spring 24 which will normally hold said latch in hooked engagement with a side projection 18^b on a stop arm part 18. The latches 21 extend through slots in the 10 transverse bar 12 so as to be held against sidewise movement, as are also the index members 15 extending through slots in the bars 12 and 13, and working freely in said slots.
- 15 Projecting upward from one member of each yoke 19^a is an arm 19^b which carries an adding segment gear 19. Extending forward from each yoke section 19^a is an arm 19^c the forward end of which is beneath a projection 18^c on a stop arm member 18. Each yoke 19^a is provided with a short arm 19^d to which is connected one end of a coil spring 25 the other end of which is attached to a transverse rod 26. These springs serve 20 to hold the arms 19^b up against the projections 18^c and which projections will prevent movement of the segment gears 19 until the stop arms 18^b are released from the latches 21. Each yoke 18^a, constituting the pivotal 25 portion of a stop arm 18, is provided with a radial projection 18^d to which is connected one end of a coil spring 27 the other end of which is attached to the transverse rod 26, these springs serving to hold the said stop 30 arms 18 upward in engagement with the hooked portions of the latches 21 until the said latches are released, when the said springs will move the said stop arms upward, as denoted in dotted lines in Fig. 1.
- 35 40 Mounted on the transverse shaft 17 are bails 28 and 29, the purpose of these bails being to reset the adding member parts, or for returning the same to normal positions after they have been moved for an adding 45 operation. The bail 28 is fixed to the shaft 17 so as to be movable therewith, the ear portions of said bail being fixed to collars 30 secured to said shaft by pins 31. The bail 29 is loosely mounted on the shaft 17, an ear 50 portion of the said bail being provided with a lug 29^a to which is attached one end of a coil spring 32 the other end of which is attached to a side frame A. This bail 29 is, in the resetting operation, arranged to engage 55 the stop arms 18, while the bail 28 is arranged to engage the arms 19^b carrying the sector gears 19, as will be understood from Fig. 1.
- An ear portion of the bail 29 is provided 60 with a laterally projecting lug 29^b (see Fig. 4) arranged to be engaged by a pawl 33 pivotally connected with an ear portion of the bail 28, the said pawl being yieldingly held in contact with said lug by a spring 34 connected to a tail portion of said pawl and to 65 the bail 28. The pawl 33 is provided with a lug 33^a arranged to be engaged by the tail portion 35^a of a repeat key or lever 35 pivoted to a side frame A and having an operating handle portion 35^b extending outside of said side frame, as shown in Fig. 3. This repeat lever is held in its normal position by a coil spring 36.
- In the operation of this improved machine the operator places a finger in that one 75 of the recesses 15^a of an index member 15 which corresponds to or registers with a desired number to be registered, and then depresses the said index member slightly holding the finger in place. The downward 80 movement of the index member is limited by a stop afforded by the shoulders 15^d coming in contact with the lower slotted transverse bar 12, through which said index member slides. This downward movement of the 85 index member causes the tail portion 15^c of the said index member, and which is in contact with the looped portion 21^a of a latch 21, to operate the said latch against the stress of its spring 24 and thus dis- 90 engages the hooked portion of said latch from the side lug 18^b of a stop arm 18. When thus released the said stop arm will be moved upward by the stress of a spring 27, carrying with it a pawl 20 the looped 95 portion 20^a of which pawl will engage the finger of the operator which is held in the finger recess in the index member 15 until such engagement occurs. For example, if the finger of the operator be placed in the 100 finger recess registering with the figure 8 on the number strip 14 the upward movement of the stop arm 18 will be arrested when the stop arm reaches the position shown in dotted lines in Fig. 1. When the looped portion 105 20^a comes in contact with the finger of the operator the pawl 20 will be rocked on its pivotal connection with the stop arm 18, thus causing a side lug 20^b on said pawl to be moved into position to engage one of the 110 ratchet teeth 15^b on the index member 15 as soon as the operator's finger is removed; (see dotted lines Fig. 1) the engagement of the lug 20^b with a tooth 15^b preventing further upward movement of the said stop arm 115 which will now remain stationary in its upward position until returned to normal position by the bail 29.
- In view of the fact that the adding sector gears 19, connected by the arms 19^b with 120 the yokes 19^a, are normally held against movement under the stress of their springs 25, by virtue of the engagement of the arms 19^c on said yokes 19^a with the lugs 18^c on the stop arms 18, it will be apparent that until 125 said stop arms are released there will be no movement of said segment gears; while an upward movement of a stop arm 18 permits a corresponding movement of an adding sector gear 19, under the influence of its 130

spring 25, to a position such, for example, as is indicated by dotted lines in Fig. 1.

The sector gears 19 co-operate with adding wheels 37 carried by pivoted arms 38, 5 and which, by appropriate mechanism not forming part of the present invention, are at proper times thrown into engagement with the adding sector gear 19. When the shaft 17 is rotated the bail 28, being 10 fastened to said shaft, as described, will rotate with it and will pick up those gear arms 19^a that have been moved to adding positions and return them to normal, at the same time rotating the adding wheels 37 15 through the gears 19 to perform an adding operation. The bail 28 will at the same time rotate the bail 29 through the pawl 33 engaging the lip 29^b and the bail 29 will then pick up and return to normal 20 the corresponding stop arms 18 of the gear arms 19^b. Thus at each release of a stop arm 18 and actuation of the shaft 17, as above described, an adding sector gear, 25 co-operating with an adding wheel, will effect a proper adding operation. If multiplication is to be effected the operator depresses and holds down the repeat key lever 35, thus disconnecting the bail 29 from the bail 28, holding the same disconnected 30 during multiplication from said bail 28. The bail 28 is then operated, through the shaft 17, for a desired number of times, the stop arm 18 meanwhile remaining in the position to which it has been moved, as 35 above described.

From the foregoing it will be apparent that in the present improved machine the index members 15 do not move or oscillate with the adding members, as in the machine 40 of my patent hereinbefore referred to, so that there is less weight of metal to be moved at each adding operation than in my former machine, and the operating speed of the machine may therefore be increased. 45 The index members 15 of the present improvement serve as triggers to release the adding members and also serve, in co-operation with the stop arms 18 and the pawls 20 carried thereby, to control the movements 50 of the adding sector gears.

It will also be apparent from the foregoing that each adding member comprises two separate parts, to wit, a stop arm part 18, and a sector gear 19, suitably connected 55 with operating means, and that while these two parts may move together for the adding operations, the sector gear part of the adding member may be operated independently of the stop arm member when multiplication is to be done.

The finger recesses 15^a and the ratchet teeth 15^b on the index members 15 afford stations, corresponding to the digits or numerals on the numeral strips 14, at which 60 the stop arms will be stopped, and at which

stations said stop arms will remain in locked engagement with the said index members when thus stopped.

The invention is not to be understood as being limited to the particular details of 70 construction herein shown and described, as such details may be varied widely, within the province of mechanical skill, without departing from the spirit or essence of the invention. 75

Having thus described my invention I claim and desire to secure by Letters Patent:

1. In a calculating machine, the combination with an index member having a plurality of stations corresponding to certain digits or numerals, of an adding member comprising a stop arm part and a gear part, said parts being separate but being capable of movement together as a unit and 80 one part being capable of movement independently of the other part when desired, and means for bringing the said adding member into operative or adding position. 85

2. In a calculating machine, the combination with an index member having a plurality of stations corresponding to certain digits or numerals, of an adding member comprising a stop arm part and a gear part, said parts being separate but being capable 90 of movement together as a unit and one part being capable of movement independently of the other part when desired, means for bringing the said adding member into operative or adding position, and means for 100 returning said adding member parts to their normal positions.

3. In a calculating machine, the combination with an adding member comprising a stop arm part and a gear part, said parts 105 being capable of movement together as a unit but being separate so that when desired one part may be moved independently of the other, an index member having a plurality of stations corresponding to certain digits or numerals, and being provided with means for controlling the adding position of the said adding member, means for bringing the stop arm part of said adding member into operative position in locked 110 engagement with the said index member, and means for returning the gear part of said adding member to normal position without returning the stop arm part to normal position. 115

4. In a calculating machine, the combination with an adding member comprising a stop arm part and a gear part, these parts being separate from each other so as to be capable of independent movement when desired. 120 of an index member having stations corresponding to certain digits or numerals and comprising means whereby said stop arm part may be brought into locked engagement with the said index member at any de- 125

sired station, means for returning the adding members to normal position, and means for causing said returning means to return the gear part only of said adding member 5 to normal position when desired.

5. In a calculating machine, the combination with an adding member comprising a stop arm part and a gear part, these parts being separate from each other so as to be capable 10 of independent movement when desired, of an index member having stations corresponding to certain digits or numerals and comprising means whereby said stop arm part may be held in locked engagement with 15 the said index member at any desired station, means for returning the adding members to normal position, means for causing said returning means to return the gear part only of said adding member to normal 20 position when desired, and a repeat lever which controls mechanism whereby the said gear part of said adding member may be repeatedly operated while the said stop member part remains unmoved in locked engagement with the said index member.

6. In a calculating machine, the combination with a movably mounted index member having a plurality of stations corresponding to certain digits or numerals, these stations being afforded by finger recesses on 30 the outer side of said member and by ratchet teeth on the inner side thereof, of a stop arm, a pawl carried by said stop arm and having a looped portion embracing the outer 35 side of said index member and a toothed portion to engage the said ratchet teeth on the inner side of said index member, a spring for operating said stop arm in one direction, a spring-pressed latch for engaging a portion 40 of said stop arm to hold it in normal position against the stress of said spring, said index member having a tail portion which, when the said index member is moved downward, will release said latch and permit said stop 45 arm spring to move said stop arm upward, a gear part, a spring for operating said gear member in one direction, means on said stop arm and connected to said gear member for holding the latter in a normal or inoperative 50 position, said means permitting said gear part to be moved independently of said stop arm, means for returning the said stop arm to normal position after having been operated,

and means whereby the said gear part may be returned to normal position without disturbing the said stop arm. 55

7. In a calculating machine, the combination with a suitable frame, of a series of strips attached to said frame and each provided with a series of digits or numerals, a series of spring-held and movably mounted index members having stations corresponding to the said digits or numerals on said numeral strips, adding members each comprising a stop arm part and a gear part, 60 said gear part being movable independently of said stop arm part, means for holding said adding member parts in normal or inoperative position, means for releasing said holding means when an index member is 65 moved downward, springs for moving said adding member parts to adding position when thus released, and means for holding each stop arm part in locked engagement with an index member, at any desired station, when the adding member parts are moved to adding position. 70

8. In a calculating machine, the combination with a suitable frame, of a series of strips attached to said frame and each provided with a series of digits or numerals, a series of spring held and movably mounted index members having stations corresponding to the said digits or numerals on said numeral strips, adding members each comprising a stop arm part and a gear part, said gear part being movable independently of said stop arm part, means for holding said adding member parts in normal or inoperative position, means for releasing said holding means when an index member is moved downward, springs for moving said adding member parts to adding position when thus released, means for holding each stop arm part in locked engagement with an index member, at any desired station, when the adding member parts are moved to adding position, and resetting means by which said adding member parts may be returned to normal positions together, or by which the gear parts of said adding members may be returned without disturbing the stop arm parts, when desired. 85

In testimony whereof I affix my signature.

WILLIAM P. QUENTELL.
